UNITED STATES PATENT OFFICE

ORA E. NEITZEL, OF SOUTH BEND, INDIANA

DESIGN FOR A GAME BOARD

Application filed May 26, 1931. Serial No. 39,991. Term of patent 3½ years.

To all whom it may concern:

Be it known that I, ORA E. NEITZEL, a citizen of the United States, residing at South Bend, in the county of St. Joseph and State of Indiana, have invented a new, original, and ornamental Design for Game Boards, of which the following is a specification, reference being had to the accompanying drawings, forming part thereof.

I claim:—

The ornamental design for a game board as shown.

ORA E. NEITZEL.
